J. W. TAGGART

PAPER BAG

Filed Jan. 14, 1925

UNITED STATES PATENT OFFICE.

JOSEPH W. TAGGART, OF WATERTOWN, NEW YORK, ASSIGNOR TO TAGGART BROTHERS COMPANY, OF WATERTOWN, NEW YORK, A CORPORATION OF NEW YORK.

PAPER BAG.

Application filed January 14, 1925. Serial No. 2,347.

This invention relates to paper bags in general, and has particular reference to the production of the heavier and coarser bags, commonly used for bagging coal, cement, 5 flour and other pulverized products, and has for its particular object to provide novel, simple, durable and strong means for forming and closing the ends of the bags. A further object is to provide a bag of the class which 10 is made from prepared tubular stock, in one or more ply, wherein the opposite ends are doubled or folded upon themselves in opposite directions, in a manner to effectually seal as well as to reinforce the said ends, for preventing breaking and tearing, or leakage of 15 the contents of the bags. A further object is to provide certain of the bags with a valve, by means of which the bags may be filled, the said valve preferably being formed out of 20 the material of the bag, and being protected for its full length, by the adjacent folded end portion, in a manner to render the bag, in the vicinity of the valve, as strong as the other portions of the bag. A further object is to 25 provide novel, simple and powerful means for securing the end-folds of the bag. The said means preferably comprising wrought metal staples, which are driven through the several folds at each end of the bag, the said 30 staples finally being clinched, in a manner to provide link-like binders or fasteners, that will not yield, or become unclinched, by the pressure of the contents, or by rough handling of the bags. And a further object is to 35 generally improve, simplify and render durable and indestructible the ends and the adjacent body portions of paper bags of the class.

I attain these objects by the means set forth 40 in the detailed description which follows, and as illustrated by the accompanying drawing, in which—

Figure 1 is a plan view of the tubular blank, from which the bags are formed. Fig. 45 2 is an edge view of the same, showing the valve relatively to the foldable top end portion. Fig. 3 is a similar edge view, showing by dotted lines the first step of the folding and closing of the ends of the tube; also showing by the full lines, the final folding steps, and the stapling or binding of the said ends. Fig. 4 is a side elevation of the device shown in Fig. 3. Fig. 5 is a reduced broken expanded edge view; showing one corner of the 50 blank slotted for providing the valve-flap. Fig. 6 is respectively a contracted and expanded view of the same; showing the severed valve-flap folded inwardly. Fig. 7 is a partial side elevation and central longitudinal section, the section being taken on line 7—7 60 of Fig. 6. Fig. 8 is a fragmentary section, on line 8—8 of Figure 4, showing the clinching of one of the fasteners.

In the drawing, 2 represents the tubular blank, which comprises the body of the bag, 65 the said tube preferably being made of tough "rope" or other paper stocks, the said tube being shown with laterally arranged longitudinal tucks 2', by means of which the tube may be readily expanded when filled, as 70 shown in Figs. 3, 5 and 6. The tube 2 may comprise a single sheet or web of paper, as shown (exaggerated) in the drawing, or it may consist of two or more sheets, known as multiply tubes. In forming-up the bags, the 75 tube-stock, which is generally made continuous, by suitable machinery, is usually cut in lengths suitable for the different size bags. Fig. 1 shows one of such lengths. When both ends of the tube are closed by the maker, a 80 filling valve, as 3, is usually disposed at or near one of the top corners of the blank, as shown in Figs. 2 to 7 inclusive. These valves are preferably formed by slitting longitudinally, as at 3', the corresponding edges 2^a, 85 which comprise the outer margins of one of the tucks 2', as shown in Figs. 2, 5, 6 and 7, for providing an integral valve-flap, as 3^a. After the slitting is effected, the flap 3^a is folded inwardly as on a crease indicated by 90 the dotted line 3^c in Fig. 5, after which the flap 3^a is again folded downwardly and outwardly on the line 3^d of the central longitudinal crease or fold of the tuck, and on the 95 angularly converging fold lines 3^e as in Fig. 6, so that the lower edge of the folded flap 3^a extends substantially at right angles to the side edges of the blank. The slits 3' are 100 preferably arranged to provide a flap, which when folded inwardly, as shown in Figs. 2, 3, 6 and 7, its free end 3^b projects beyond the inner margin of the tuck 2'. This insures the proper filling and expanding of the bag, without danger of distorting the valve, or weakening that particular portion of the bag.

In the present showing, referring to Figs. 2, 6 and 7, the valve 3 is located a considerable distance from the top end of the tube, so as to provide a relatively long end margin or extremity beyond the valve, for use in effecting 105 110

the subsequent closing and sealing of the said end, without distorting the valve. The folding of the ends of the tubes is accomplished in the following manner: The opposite ends 2^c—2^d of the blank, shown in Fig. 2, are first folded inwardly upon the body of the tube 2, substantially at the points indicated by the broken line 2^e of Figs. 1 and 2. According to Fig. 3, the relatively long folded end portions 2^c—2^d, are next folded upwardly and downwardly respectively substantially on the line corresponding to 2^f in Fig. 1, after which the free ends of the portions 2^c—2^d are bent and folded around the ends of the tube, in a manner to dispose the said ends in close contact with the opposite face of the tube, as shown at 2^x in Fig. 3. This completes the folding of the ends of the bag, and not only tightly seals, but also greatly reinforces the said ends. The final operation consists of driving staples, as 5, through the mass of folds, as shown in Figs. 3 and 4. These staples are preferably long enough to be clinched, as shown in Fig. 8, wherein the ends of the tines 5' of the staples overlap, in a manner to form oval link-like fasteners, which are not liable to spread or become loosened by strains due to filling or subsequent rough handling of the bags. The staples 5 may be disposed in a single row across the folded end-portions of the bag, as shown in Fig. 4, or they may be arranged in staggered rows, in a well-known manner. The foregoing describes the mode and means for closing and sealing valve-bags, wherein both ends of the bag are substantially closed, and wherein the filling is effected solely by forcing the pulverized products through the relatively small valve openings 3, as by a pipe 6, shown in Figs. 4 and 7.

Obviously the same method and means may be employed for closing and sealing the bot-

toms of the valveless bags, and after the said bags are filled, the mouths or filling ends may be folded and secured, by staples, by the use of any suitable machine (not shown) in a well-known manner. My bag enclosing and sealing means are applicable to almost every form of paper bag that requires closing and sealing of the ends, for protecting the contents, and for insuring the safe handling of the bags after they are filled.

Having thus described my invention, what I claim is—

1. In a bag, the combination of a prepared tubular blank having a flexible square cut end and lateral longitudinal tucks, corresponding margins of one of said tucks at one corner of said square end of the blank being slitted longitudinally to provide a valve flap comprising only the web of the tuck and which is folded inwardly and then downwardly between the walls of said tuck on the central line of fold of the tuck and on diagonal fold lines converging at a point lying within said central line of fold, the end portions of the blank for the full width of the blank at said end thereof above the inner end of the valve flap being folded inwardly upon one side of the body of the blank and secured thereto. 70

2. In a bag, the combination of a prepared tubular blank having a flexible square cut end and lateral longitudinal tucks, corresponding margins of one of said tucks at one corner of said square end of the blank being slitted longitudinally to provide a valve flap comprising only the web of the tuck and which is folded inwardly and then downwardly between the walls of said tuck on the central line of fold of the tuck and on diagonal fold lines converging at a point lying within said central line of fold. 80

In testimony whereof I affix my signature.
JOSEPH W. TAGGART.
